UNITED STATES PATENT OFFICE.

FREDERICK A. BRADWAY, OF MONSON, MASSACHUSETTS.

WATER-MOTOR.

SPECIFICATION forming part of Letters Patent No. 729,917, dated June 2, 1903.

Application filed March 9, 1903. Serial No. 146,808. (No model.)

To all whom it may concern:

Be it known that I, FREDERICK A. BRADWAY, a citizen of the United States of America, and a resident of Monson, in the county 5 of Hampden and State of Massachusetts, have invented certain new and useful Improvements in Water-Motors, of which the following is a full, clear, and exact description.

This invention relates to improvements in water-motors of a class comprising a casing having a bucket-wheel therein mounted on a motor-driving shaft and having an inlet-chamber with which one or more guides are 15 connected for guiding the water onto the bucket-wheel.

The objects of the invention are to simplify the construction of the motor, to render the same available for the use of one or more streams of water against the bucket-wheel for the greater or less power, as required, with a corresponding expenditure of water, and to insure means for the most effective direction of the water in relation to the bucket-wheel.

The invention consists in the constructions and arrangements of parts, all substantially as hereinafter described, and set forth in the claims.

Reference is to be had to the accompanying drawings, in which—

Figure 1 is a side view, Fig. 2 a front view, and Fig. 3 a plan view, of the motor. Fig. 4 is a vertical sectional view on line 4 4, Fig. 2; and Fig. 5 is a horizontal sectional view on line 5 5, Fig. 4. Fig. 6 is a sectional view through the casing and water-guides of a motor having arrangements for driving streams against the bucket-wheel at its side and bottom. Fig. 7 is a horizontal sectional view on line 7 7, Fig. 6; and Fig. 8 is a side elevation of the motor.

Similar characters of reference indicate corresponding parts in all of the views.

Referring more particularly to Sheet 1 of the drawings, A represents the casing of the motor, formed sectionally with lugs through which the parts are bolted together, as indicated at a, the same having a chamber B therein for accommodation of the bucket-wheel C, which is shown as mounted on the shaft D, having bearings in and through the opposite sides of the casing and provided with the

pulley or driving wheel E, and the bucket-wheel is shown as formed duplex—that is, with two sets of edgewise-open buckets b arranged side by side and separated by the central partition e. The casing has at its top and toward the front the opening f, above which is located and adjustably secured the chest or box F, which is provided with a pipe-section 55 or waterway g and preferably with two of such pipe-sections, which protrude downwardly through and below the said opening f, and receiving the water-guides G, vertically adjustable thereon. H represents the water inlet and supply passage leading into the chest F, and J represents the outlet or waste passage of the motor at its bottom. The water-guides are shown as in the form of tubes telescopically fitting and adjustable axially 70 on the pipe-extensions g, being secured to another vertical adjustment by the set-screws i, the faces thereof toward the bucket-wheel conforming to the circumferences thereof, such guides being curved somewhat, as shown 75 in Fig. 4. In order that the water-guides, which are vertically adjustable on the pipe-sections g, of and downwardly extended from the chest F, may have their locations in exactly the proper and most effective proximity 80 to the wheel, the chest is rendered horizontally adjustable forward and back by having in the fitting-lugs j thereof the elongated slots j², through which the confining headed screws or bolts j³ are passed, the latter having a 85 screw engagement into the top wall of the motor-casing. Packing k is shown as interposed between the bottom of the chest and the top of the casing. The possibility of acquiring all adjustments to bring the guides 90 to the proper proximity to the buckets of the wheel and to have them at such height as to have a direction of the water for the best driving action against the wheel is acquired by the means above set forth, and in order that 95 any back pressure of the water may not force the guides g outwardly unduly away from the edge of the wheel an abutment is provided transversely against each water-guide, the same, as shown in Fig. 4, consisting in a screw 100 o, adjustably engaging in a horizontal line through the front wall of the casing. Each of the passages through the portions g downwardly leading from the chest F may be closed

by a valve m individual thereto, the same, as shown, consisting of a slide-block having racked teeth in its top, with which engages a tooth-ended lever m^2 , carried on a rock-shaft 5 n , extended through the bearings and packings horizontally to the exterior of the chest and having a handle n^2 for imparting a rocking movement to the rock-shaft. One valve may be left open and the other closed, both 10 may be open or both closed, for the manifest effects resulting from such conditions. The casing is shown as having in its front an opening p and laterally-extended flanges q , such opening permitting the insertion to 15 place an adjustable connection of the water-guides, and for such opening is the front closing-plate r , secured by screws or bolts s , which engage into the aforementioned flanges q . In one or both sides of the casing 20 opposite the lines of proximity of the guides g and edge portions of the buckets are glass-closed openings t , the transparent closing sections t^2 being held in place by any suitable fastening means, such transparent sections 25 of the side walls permitting to be seen from the outside whether or not the water-guides are maintained in their proper and effective relations to the bucket-wheel.

In Sheet 2 of the drawings an adaptation of 30 the motor is illustrated for the employment of one or pairs of the water-guides for bringing approximately vertical and horizontal streams against the bucket-wheel C, the general organization of the motor being substantially as described in connection with the drawings of Sheet 1, but embodying an additional chest F^2 and made vertically adjustable at the lower front portion of the motor in proximity to the motor-front opening f^2 , the 35 vertical adjustment of the chest being, by the lug construction j^* and confining-screws, substantially as described for the adjustment of the top chest F. The chest F^2 has the pipe extension g^2 or extensions receiving telescopically and adjustably the horizontally-extending water-guides G^2 , having their locations in proximity to and under the bucket-wheel. The conductor or conduits M lead from the upper chest above the valve or valves 40 therein down into the lower chest, and, as shown, this conduit comprises a screw-coupling section u , connecting into the intermediate coupling (in which is the valve v) and into the top of the lower chest, so that by 45 turning this section when desired to slightly raise or lower the lower chest such section adjustably conforms to the changed position of the chest. By having individual valves m^* for each downwardly-leading waterway g and 50 having individual valves v in the conduits M it is possible where upper and lower pairs of water-guides are employed to drive the shaft of the motor through the bucket-wheel with a single stream or two, three, or four streams, 55 distributed at the will of the user of the apparatus.

This motor is intended generally to be con-

nected with some water-supply pipe and is susceptible of the variable manners of use in accordance with the pressure conditions 70 available and the work to be imposed upon the motor.

Having thus described my invention, what I claim, and desire to secure by Letters Patent, is—

1. In a water-motor, in combination, a casing having a water-wheel journaled therein and having an opening at its top, a chest mounted at the top and adjustable transversely of the casing, having a water-inlet 80 and a pipe-section depending through the top opening of the casing, and having a curved water-extension guide, directed toward the wheel and vertically adjustable on said depending pipe-section. 85

2. In a water-motor the combination with a water-wheel having two series of buckets in different parallel planes and a casing in which said wheel is journaled having an opening in its top, of a water-chest at the top of the casing transversely adjustable having an inlet-opening and having depending water-conduits extending through said opening, and directed toward the respective series of buckets, and valves individually provided to the 95 respective depending conduits, and means for separately operating them.

3. In a water-motor the combination with a water-wheel having two series of buckets in different parallel planes and a casing in which 100 said wheel is journaled having an opening in its top, of a water-chest at the top of the casing transversely adjustable, having an inlet-opening, and having depending water-guides extending through said opening, and directed 105 toward the respective series of buckets, valves sliding on the base of the water-chest adjacent the upper orifices of the depending conduits having toothed tops, rock-shafts journaled through the walls of the chest and provided 110 respectively with the tooth-ended levers engaging in said valve-teeth, and means for imparting rocking movements to said shaft.

4. In a water-motor, in combination, a casing having a water-wheel journaled therein, 115 and having an opening at its top, a chest mounted at the top of the casing transversely adjustable thereon, having a water-inlet and a pipe-section depending through the top opening of the casing, a water-guide G having 120 a tubular upper portion telescopically adjustable on said pipe-section, and having its lower portion in the form of a channel curved and with the channel opening toward the wheel, and the confining-screw i for holding said 125 guide in its adjusted position.

5. In a water-motor, in combination, a casing having a water-wheel journaled therein, and having an opening at its top, a chest mounted at the top of the casing transversely 130 adjustable thereon, having a water-inlet and a pipe-section depending through the top opening of the casing, a water-guide G having a tubular upper portion telescopically adjust-

able on said pipe-section, and means for holding it in its adjusted position, and an adjustable abutment *o* for reinforcing the guide in its position adjacent the wheel.

5 6. In a water-motor, in combination, a water-wheel and an inclosing casing therefor having at its top and also at its front, openings *f* and *f*², chests *F* and *F*² mounted and respectively horizontally and vertically adjustable on the top and front of the casing, and having the inwardly-extending pipe-sections *g* and *g*² with continuations directed toward the front and bottom edges of the wheel, a water-inlet to the upper chest, and a conduit leading from the upper chest to the lower chest.

15 7. In a water-motor, in combination, a water-wheel and an inclosing casing therefor having at its top and also at its front, openings *f* and *f*², chests *F* and *F*², mounted and respectively horizontally and vertically adjustable on the top and front of the casing, and having the inwardly-extending pipe-sections *g* and *g*² with telescopic tubular continuations directed and curved toward the front and bottom edges of the wheel and adjustable along

said pipe-sections *g* and *g*², a water-inlet to the upper chest, and a conduit leading from the upper chest to the lower chest.

8. In a water-motor, in combination, a water-wheel and a casing inclosing same, having at 30 its top and also at its front, openings *f* and *f*², the chests *F* and *F*² mounted and respectively horizontally and vertically adjustable on the top and front of the casing and having the downwardly and horizontally inwardly extending pipe-sections *g* and *g*² continued toward the front and bottom edges of the wheel, a water-inlet to the upper chest, a conduit leading from the upper to the lower chest, a valve in the upper chest opening and closing 35 communication between same and the pipe-section *g*, and a valve in the chest-connecting conduit, for the purposes set forth.

Signed by me at Springfield, Massachusetts, in presence of two subscribing witnesses.
